UNITED STATES PATENT OFFICE.

PHILEMON O. DICKINSON, OF NEWARK, NEW JERSEY.

DESIGN FOR A BACK FOR BRUSHES, &c.

SPECIFICATION forming part of Design No. 24,981, dated December 17, 1895.

Application filed November 14, 1895. Serial No. 568,975. Term of patent 3½ years.

To all whom it may concern:

Be it known that I, PHILEMON O. DICKINSON, a citizen of the United States, residing at Newark, in the county of Essex and State 5 of New Jersey, have invented and produced a new and original Design for Backs for Brushes and Similar Articles, of which the following is a description, reference being had to the accompanying drawing, which illustrates the 10 design.

The general outline of the back is a rectangle having the two ends and corners slightly rounded. Just within the edge and running along the straight sides of the same is a border-band A A. At the ends of the brush are the 15

rococo wreaths B B, inclosing plain surface C C, and at the middle of the handle is the rococo shield D, extending from one border-band A to the opposite border-band.

The essential features of the design are 20 those above recited.

What is claimed as new is—

The design for backs of brushes and similar articles, substantially as herein shown and described.

PHILEMON O. DICKINSON.
